EXHAUST STEAM SPREADER

Filed Feb. 16, 1931

UNITED STATES PATENT OFFICE

JOHN G. NORQUAY, OF ST. ANDREWS, MANITOBA, CANADA

EXHAUST STEAM SPREADER

Application filed February 16, 1931, Serial No. 515,981, and in Canada August 5, 1930.

The invention relates to improvements in exhaust steam spreaders and particularly to an exhaust steam spreader for use on the nozzle stand of a locomotive and an object of 5 the invention is to provide a device which can be readily mounted on the upper end of the nozzle stand and will operate to spread exhaust steam as it passes upwardly to the smoke stack and to distribute the steam evenly over the entire cross sectional area of the stack, such insuring of the effective discharge 10 of the products of combustion from the smoke box through the stack.

A further object of the invention is to 15 provide a spreader of simple design and of inexpensive construction and which can be placed on existing nozzle stands without requiring any alteration in the structure thereof and also which can be mounted on the 20 stand without requiring to dispense with the existing nozzle.

With the above more important and other minor objects in view, the invention consists essentially in the arrangement and construction 25 of parts hereinafter more particularly described, reference being had to the accompanying drawing, in which:—

Fig. 1 is a vertical sectional view through the forward end of a locomotive smoke box, 30 the section extending vertically and transversely through the centre of the stack and nozzle stand.

Fig. 2 is an enlarged detailed vertical sectional view transversely through the spreader, the nozzle and the upper end of the nozzle stand.

Fig. 3 is a plan view of the spreader.

In the drawing like characters of reference indicate corresponding parts in the several figures.

The smoke stack 1 extends upwardly from the smoke box 2 and has the lower end thereof out flared as indicated at 3 and lying directly above the upper end of the conventional nozzle stand 4 which latter is provided

with an out turned flange 5. A nozzle 6 is also supplied, the nozzle being in the form of a ring inserted in the upper end of the nozzle stand and having an upwardly converging inner wall 7 and provided with an 50 outstanding flange 8 resting on the flange 5. The nozzle is fastened to the nozzle stand by a plurality of suitably spaced bolts 9 which pass through the flange 8 and screw thread into the flange 5. 55

The above parts are as customarily provided on locomotive boilers and form no part of the present invention and in this connection, it might be remarked that the exhaust steam passing up through the nozzle stand 60 is directed through the nozzle into the lower end of the smoke stack and is utilized to clear the products of combustion from the smoke box.

The spreader which I have devised comprises a plurality of inverted frusto-conically shaped rings spaced and supported above the outlet from the nozzle to spread the up passing exhaust steam and distribute it evenly over the entire cross sectional area of the 70 stack, thereby insuring of the effective clearance of the products of combustion upwardly through the stack.

In the present instance, I have shown the spreader as comprising an outer inverted 75 frusto-conically shaped ring 10 provided internally with vertically disposed thin webs 11 which support within the outer ring, an inner inverted frusto-conically shaped ring 12, the rings 10 and 12 being concentric. 80 Supporting arms 13 extend outwardly from the lower end of the ring 10 and the outer ends of these arms are provided with eyes 14 which are adapted to receive the bolts 9 hereinbefore mentioned. According to this 85 arrangement, it is only necessary to remove the existing bolts which fasten the nozzle to the nozzle stand, put my spreader in place and fasten the same to the latter parts by utilizing the bolts 9 herein shown. 90

It will be particularly observed that the bottom or contracted end of the outer ring 10 of the spreader has an external diameter somewhat less than the internal diameter of 5 the upper end of the nozzle opening so that a certain amount of up going steam is passed between the annular opening appearing between the nozzle and the lower end of the ring 10 and is spread outwardly and upwardly by 10 the outer face of the ring 10 into the lower end of the stack.

Further it will be observed that a certain proportion of the up going steam will be passed between the rings 10 and 12 and will 15 be deflected upwardly and outwardly thereby and that a certain proportion of the up going steam will be passed through the center of the ring 12. By properly positioning the rings of the spreader in regard to the upper 20 end of the nozzle and flaring the rings 10 and 12 a proper amount, I am able to spread the up going exhaust steam so that it is distributed evenly over the entire cross sectional area of the lower end of the stack and by so 25 doing, insure of the effective clearance of the products of combustion from the smoke box through the stack.

It will be particularly observed that this device can be installed on existing locomotives 30 without requiring to alter any existing structure and that it in no way interferes with the nozzle and permits of the ready changing of the nozzle as and when required.

What I claim as my invention is:—

35 An exhaust steam spreader comprising concentrically positioned and spaced inverted frusto-conically shaped rings supported one from the other by intervening relatively thin vertically disposed webs and having the 40 outer ring provided with a plurality of outwardly extending supporting arms provided at their outer ends with fastening means.

Signed at Winnipeg this 17th day of December 1930.

JOHN G. NORQUAY.
